UNITED STATES PATENT OFFICE.

THOMAS H. KANE, OF YOUNGSTOWN, OHIO, ASSIGNOR TO THE TRUSCON STEEL COMPANY, OF YOUNGSTOWN, OHIO, A CORPORATION OF OHIO.

FRAMING CLAMP.

Application filed January 31, 1921. Serial No. 441,249.

To all whom it may concern:

Be it known that I, THOMAS H. KANE, a citizen of the United States, residing at Youngstown, in the county of Mahoning 5 and State of Ohio, have invented certain new and useful Improvement in Framing Clamps, of which the following is a specification.

This invention relates to an improved 10 framing clamp for connecting crossing elements such as the structural members in a fireproof building construction.

A primary object of the invention is to provide a clamp of a simple and practical 15 construction capable of being readily used as a securing means for clamping together structural parts, and to that end it is intended to be especially useful as a framing clamp for connecting the metallic structural parts in a fireproof building operation, to thereby avoid the use of bolts or rivets and obviating the customary drilling or welding operations with their consequent expense in time and labor. It is 20 also the purpose of the invention to provide a clamp of the type referred to which will connect the assembled parts in a thoroughly practical and rigid manner and also to provide a clamp which may be easily 25 and quickly applied by unskilled labor in the operation of holding together such structural parts as beams, studs, bars and the like. Also the invention contemplates a framing clamp which functions very 30 effectively in connecting together the vertical frame bars of curtain walls, with the sill angles in building construction.

A further object of the invention is to provide a clamp whose parts may be readily 40 assembled and applied and quickly adjusted into the desired position for holding the structural parts together.

With the above and other objects in view, which will more readily appear as the nature 45 of the invention is better understood, the same consists in the novel construction, combination and arrangement of parts hereinafter more fully described, illustrated and claimed.

50 In the accompanying drawings:

Figure 1 is a side elevation of one embodiment of the invention applied to crossing structural members.

Figure 2 is a horizontal sectional view 55 taken on the line 2-2 of Figure 1.

Figure 3 is an elevation of one side of the body or fulcrum element of the clamp shown in Figures 1 and 2.

Figure 4 is a top plan view of a modified form of clamp. 60

Figure 5 is a side elevation of the type of clamp shown in Figure 4.

Figure 6 is an elevation of one side of the body element of the type of clamp shown in Figures 4 and 5. 65

Figure 7 is a view illustrating the application of a still further modified type of clamp. 70

Figure 8 is a horizontal sectional view taken on the line 8-8 of Figure 7.

Figure 9 is an end elevation of the members constituting the framework engaging clip of the type of clamp shown in Figures 7 and 8. 75

Figure 10 is a perspective view of the combined key and clamp element used in Figures 7, 8 and 9.

Figure 11 includes side elevations of the members of the clip shown in Figure 9. 80

Similar reference numerals designate corresponding parts throughout the several figures of the drawings.

As previously indicated, the present invention primarily contemplates a simple and economical framing clamp for securely holding together crossing members at their points of intersection, and is of special utility as a clamp for the structural frame elements of fireproof buildings, as shown for example in my pending application 90 Serial No. 434044 filed December 30, 1920. 85

In carrying forward the general objects of the invention, a clamp is provided which in all of its embodiments, includes certain essential elements cooperating to securely bind or connect the crossed parts or members to be united and to that end, the clamp preferably includes in combination, a clip element designated generally as A, a clamping plate B, and a locking or tensioning 100 device C which may be quickly assembled and applied by unskilled workmen and readily adjusted to final position.

Referring first to the embodiment shown in Figures 1 to 3 inclusive, that form of the invention includes a clip element A of substantially U-shaped formation, having the inturned relatively contractible hook-shaped ends 1 for engaging with the flanges of an I-bar 2 or the like, while the body 110

thereof is formed into a looped key portion 2 adapted to project through an opening 3 in the wall 4 of the clamping plate B. To give the said plate B the desired stiffness it is preferably of channeled formation, having the side flanges 5 and provided at one end with the offset bearing foot 6, while the edges of the flanges 5 at the opposite end of the plate constitute a bearing 6^a for engaging with the member y disposed at right angles to the structural member x. When the clamping plate is assembled in operation relative to the clip, the said side flanges 5 also cooperate with the shanks of the hooks 1 to prevent the same from spreading.

The portion of the loop 2 of the clip element extending beyond the outer face of the wall 4 of the plate B receives a suitable wedge or equivalent locking element 7 in such a manner that when the wedge is driven into the loop by a hammer blow, the force of the latter will have the effect of drawing the loop of the clip through the opening or eye 3 and at the same time forcing the ends of the flanges 5 of the clamp firmly into engagement with the part y. Thus, with the hook portions 1 of the clip in the foot 6 working in opposition to the bearing end 6^a of the clamping plate B, the abutting faces of the members x and y will be securely bound and clamped together. When the wedge 7 is driven into final position, the relative resiliency of the parts of the clamp will materially increase the grip of the hooks of the clip on the structural members by compressing the side members of the loop portion 2, thus materially augmenting the rigidity of the connection.

In the embodiment of the invention shown in Figures 4 to 6 inclusive, the same essential features are observed. In this embodiment, the clip element A' is preferably in the form of a bolt having the threads 9 while the inner end thereof is provided with the hook portions 10 for engaging with the structural member x, and the said threaded shank of the bolt projects through the opening 11 in the wall of the plate 12 which constitutes the body B of the clamp to receive the nut 13. Upon tightening the nut on the threaded portion of the shank of the bolt, the members x and y will be securely clamped together in the same manner as by the clamp shown in Figures 1 and 2, since the plate 11 has at one end the bearing foot 14, and at its other end the bearing edges 15. It will also be observed that in this form the clamping plate B is of channel formation to give the same the desired stiffness while the flanges 12^a are provided at their intermediate portions with the offset lips 12^b which bear against the shanks of the hooks 10 in such a way as to prevent spreading thereof when the clip is placed under tension.

Another modified form of the invention is shown in Figures 7 to 11 inclusive wherein in the clip A² is held in operative position by means of a combined clamping and wedge element C². In this construction, the clip element A² is preferably divided into complementary members 16 and 17, having at their inner edges the hooks 18 and 19 respectively for engaging for example with the structural member x, while their opposite edges are formed with the matching knuckle elements 20, 20^a and 21 respectively, resembling the matching knuckles of a hinge. When in assembled relation, the knuckle portions 20 and 20^a of the member 16 will align with the single intermediate part 21 of the member 17 to provide a continuous wedge receiving opening z as shown in Figure 8, and when thus properly positioned with reference to each other, the combined clamping and locking wedge element C² may be inserted in position.

Upon reference to Figure 10 of the drawings, it will be observed that the wedge element C² is provided with an abutment foot 22, and a cut away tapering edge portion 23 which provides a clamping edge 24 for engaging with one of the structural members y, while the clip engaging edge 25 at the opposite side is adapted to slidably engage in the opening formed by the matching of the knuckles 20, 20^a and 21. When the locking wedge C² is driven into position, it maintains the members 16 and 17 in assembled relation, and by reason of the taper of the members along the knuckle edges thereof, the said wedge will effectively force the members of the clamp outwardly resulting in securing clamping together the parts x and y.

From the foregoing description and the accompanying drawings it is believed that the manner of applying the present clamp will be apparent, and it is also believed that it will be readily understood by those skilled in the art that all forms of the clamp are capable of simple and facile application and adjustment. And, while several forms of the invention are shown and described in the present description and drawings, it will of course be understood that other changes in the form, proportion and minor details of construction may be resorted to without departing from the spirit of the invention or scope of the appended claims.

I claim:

1. A clamp of the class described including in combination with the parts to be joined, a clip element having relatively contractible hook portions for engaging one of said members, a clamping plate having a bearing engagement with one of said members and a clamping engagement with the other of said members, and a locking device engaging the clip and said clamping

plate thereby causing the contraction of the hook portions of the clip.

2. A clamping device including in combination with the members to be joined, a bifurcated clip having oppositely arranged hook portions adapted to engage with one of said members, a clamping plate, and means for causing the said clip and clamping plate to be shifted in opposite directions to force 10 the parts to be joined rigidly together.

3. A clamping device including in combination with the members to be joined, a bifurcated clip having relatively contractible means for engaging with one of said 15 members, a clamping element adapted to have a bearing engagement with the member engaged by the clip and also adapted to have a clamping engagement with the other member, and means for forcing the said clip and 20 clamping element together.

4. A clamping device including in combination with the members to be joined, a bifurcated clip having relatively contractible hook portions for engaging with one of 25 said members, a clamping element adapted to receive a portion of the clip, and means engaging the clip and having an abutting engagement with the clamping element for shifting the clip and clamping element in 30 opposite directions.

5. A clamping device including in combination with the members to be joined, a bifurcated clip having relatively contractible means for engaging with one of said 35 members and also having a shank portion, a clamping element having an opening for receiving the shank of the clip, and means adapted to engage with

the shank of the clip for shifting the clamping plate toward the member engaging 40 end of the clip thereby to cause the relatively contractible means of said clip to grasp one of said members.

6. A clamping device including in combination with the members to be joined, a 45 clip having means for engaging with one of said members and also having a shank portion, a clamping element having a bearing foot at one end for engaging with said member engaged by the clip while the opposite end thereof is adapted to engage with the other member of the joint, said clamping element also having an opening for receiving the shank portion of the clip, and means adjustably engaging the shank portion of the clip at one side of the clamping element for forcing the same into position 50 to clamp the members to be joined.

7. A clamping device including in combination with the members to be joined, a 60 clip having hooks at one end for engaging with one of the said members and having a projecting portion adapted to receive a locking device, a clamping element having an opening for receiving the said projecting 65 portion of the clip, and a locking device carried with the said clip and engaging with the clamping element thereby to cause the contraction of the hooks at the end of the clip.

In testimony whereof I hereunto affix my signature in the presence of two witnesses.
